KEY CHAIN

John M. Grace, Chicago, Ill.

Application June 18, 1952, Serial No. 294,214

5 Claims. (Cl. 70—457)

My invention relates to key chains and to a method 15 for their assembly or manufacture.

Novelty items, particularly those items which embody a trick or puzzle, have always taken the eye of the American people. In addition to enormous sales of such items over retail counters, the nation's advertisers have placed gratuitously in the hands of the public millions upon millions of one ingenious device after another, carrying a small advertising legend for numerous services and articles of manufacture. Key chains, being inexpensive and always useful, are popular advertising premium items and favorite targets for the application of ingenuity.

In my experience, key containers fall into several general types, none of which is wholly satisfactory. One example is a plain rod-and-bead chain, the ends of which are joined together by a doubly cupped container to hold the two end beads, the cups being slit for a snap passage of the rods to the bottoms of the cups. When such a chain is new, the slit in the cup is frequently too tight for convenient opening and closing, and after a few such openings and closings, the rod either becomes weakened and breaks or the slit opens up so that the bead is not firmly held. Furthermore it lies within common experience that removing a single key from the chain without having all of the keys fall off can be accomplished only by the most expert and delicate manipulation.

Another frequently seen type of key container involves, usually with a leather case, a short headed shaft, internally threaded, and a headed bolt which is screwed into the shaft. The bolt in this type of container is invariably soon lost or tightened down so tightly that it cannot be removed by the fingers. A third type consists of, usually, several snap hooks mounted in a leather case. This kind is bulky, and after a few changes of keys, the hooks become spread so that they no longer hold a key securely.

A primary object of my invention therefore is the provision of a key chain which holds a quantity of keys safely and securely with a minimum possibility of the accidental loss of a key therefrom, and yet which permits exceedingly easy removal when desired.

Another object of my invention is the provision of a key chain which is not bulky and which is not exposed to any sort of appreciable wear in the placing on or removal of a key from the chain.

Still another object is to provide a key chain which is characterized by the ingenious and puzzling way in which keys are put on or taken off it.

Another object is the provision of a chain which has an integral part thereof a member providing space for a brief advertising message, or insignia.

Still another object of my invention is the provision of a key chain which while meeting the above qualifications, is simple and attractive in appearance.

It of course is well known that articles of this type, and particularly those which are to be used as advertising media and given away, must be made inexpensively, and

2

therefore a still further object of my invention is the provision of a novel method of manufacture of this ingenious key chain whereby it may be produced at very low cost, without sacrificing any part of its attractiveness.

5 Other objects and advantages of my invention will be apparent from the following description and drawings of which:

Fig. 1 is a plan of the key chain embodying my invention shown with a key mounted on it;

10 Fig. 2 is a plan similar to Fig. 1 showing, however, the method by which a key is put on or taken off the chain;

Fig. 3 is an enlarged plan, broken away in part to a section, of the left hand end of Fig. 1; and

Fig. 4 is a plan similar to Fig. 3 broken away in part, illustrating a stage in manufacture.

The key chain embodying my invention comprises in general three parts; a loop 10, a chain 12, and a fob 14. In the illustrative embodiment, the loop 10 is preferably composed of a length of a stiff but highly resilient and strong wire 16 such as music wire, about an inch and a half long, which is bent through somewhat more than 180° and having relatively straight end portions 18 on either side of the bend. As illustrated, the loop has somewhat the shape of a horseshoe. At its extremities the wire is bent back on itself to define eyes 20. The loop is substantially encased in a length of plastic tubing 22 which may be of the polyethylene type, this material being flexible and resilient and having both an appearance and a texture which is pleasing in the instant application. This tube 22 is of a length to leave only the ends of the eyes 20 visible, or, in other words, covers the free ends of the wire, for the sake of appearance as well as to prevent the free ends of the wire snagging in pockets or purse linings and to keep the chain from pulling out of the eyes 20.

The chain 12 is about four inches long and is hooked at its ends to the eyes 20. The chain should be of a highly flexible type, i.e., a type which can be doubled back on itself without substantial looping. The importance of this flexibility will be shown later. The link type illustrated and the woven type chain would be suitable examples. The essential dimensional limitation on the chain 12 and the loop 10 is that their combined total diameter be appreciably smaller than the eye 24 of a conventional key 26. I have found a combined diameter of about $\frac{5}{32}$ inch entirely suitable. This permits the use of chains which are strong enough for the purpose and at the same time will accommodate keys with relatively small eyes. The remaining component, the fob 14, is, in the illustrated embodiment, a flat metal stamping having a hole 28 formed therein by which it is strung on the chain 12. The illustrated fob is blank and suited for the printing or stamping thereon of an advertising message. Where the chain is not intended for advertising use the fob may take the form of any ornamental design or figure. Its sole dimensional requirement is that it be larger than an eye of a key, to keep the key on the chain.

60 The way in which this key chain is constructed is as follows: The music wire 16 is first cut to the proper length and bent to the appropriate curvature, and one, somewhat open eye 20 is formed therein at one extremity thereof. The chain 12 is then connected at one of its ends to this open eye and the eye then closed. The plastic tubing 22 is then placed on the wire 16 and slid over the already formed eye 20 so as to leave the other end of the wire substantially clear for manipulation. The requirement that the tubing be capable of being stretched, or at least flattened, to cover the one eye as to 30 (Fig. 4), imposes limitations on the type of plastic used. As pointed out

above I prefer a polyethylene type, but other flexible materials will serve. The other eye 20 is then formed in the free end of the wire, the fob threaded on the chain, the other end of the chain 12 secured to the eye, and that eye closed. The plastic tubing 22 is thereupon backed off the first formed eye which it covers entirely so that it now covers the free ends of the wire but leaves the ends of the eyes exposed. The plastic tubing is thereafter maintained in its proper position by the two eyes and, in turn, prevents in positive fashion the chain coming off the ends of the wire 16, and the ends of the wire catching in pocket linings, etc.

If the showing of Fig. 1, alone is considered, it will be noted that the way in which the key is removed from the chain is by no means apparent. I have found, by trying out the key chain among my friends, that the time required for adults to arrive at the solution is between one and ten minutes. The secret is disclosed in Fig. 2, which shows a key approximately half on or half off. A key is put on the chain by passing the loop 10 through the eye 24 of the key 26, the chain end attached to the entering end of the loop following through with the loop. After the loop 10 has passed completely through the eye of the key, the chain and key appear as illustrated in Fig. 1, the eye 24 of the key 26 containing both sides of the chain with respect to the fob 14 and being held on the chain by the loop 10 at one end and the fob 14 at the other. The procedure for removing the key is the same, the loop is simply threaded back through the eye 24 of the key, the chain end attached to the leading loop eye following through with the loop. It is in connection with putting on and taking off keys that the flexibility of the chain becomes critical. The chain must be capable of being doubled back on the loop to lie flat against it. If it were to bulge away from the loop to the extent of exceeding the diameter of the key eye 24, then obviously, the loop could not be threaded through the key eye and thus the key could not be put on the chain.

Having thus described a preferred embodiment of my invention I claim and desire to secure by Letters Patent:

1. A key chain adapted to have a key mounted thereon, said key having an eye therein spaced from the periphery of said key, comprising a length of curved music wire, the curvature of said wire being such that the distance between the ends of said wire is greater than the space between said key eye and the portion of the key periphery nearest said eye, a plastic tubular covering for said wire,

5 a flexible chain secured at its ends to the ends of said wire, and a fob, having a hole therein, threaded on said chain.

2. A key chain comprising a length of music wire having a curvature of about 180°, a plastic tubular covering for said wire, a flexible chain secured at its ends to the ends of said wire, and a fob, having a hole therein, threaded on said chain.

10 3. A key chain comprising a length of music wire bent to have a curvature of between 180° and 270° intermediate its ends, and to have eyes at the ends thereof formed by doubling back the extremities of the wire on itself, a tubular plastic covering mounted on said wire to overlie said extremities but to leave a portion of said eyes uncovered, a flexible chain secured at its ends to said eyes and a fob, having a hole formed therein, threaded on said chain.

15 4. A key chain comprising a length of resilient music wire formed into a generally horseshoe shape when not compressed, with eyes at each end thereof, a plastic tubular covering for said wire, a flexible chain secured at its ends to said eyes in said wire, and a fob having a hole therein slidably threaded on said chain.

20 5. A key chain comprising a length of resilient music wire bent into a generally horseshoe shaped configuration and having eyes at the extremities thereof formed by doubling back the ends of the wire on itself, a flexible tubular plastic covering mounted on said wire to overlie said wire ends but to leave a portion of said eyes uncovered, a flexible chain secured at its ends to said eyes, and a fob slidably mounted on said chain intermediate of the ends of said chain.
